UNITED STATES PATENT OFFICE

FREDERICK G. YAWMAN, OF ROCHESTER, NEW YORK, ASSIGNOR TO ROLAND A. FURLONG, OF ROCHESTER, NEW YORK

VISIBLE INDEX

Application filed May 25, 1931. Serial No. 539,797.

This invention relates to card indexes and has for its principal object to provide movable retaining devices for the card holders whereby one or as many card holders as may be convenient, may be freed so as to permit their ready removal from the tray. The improved retaining devices normally overlie the ends of the card holders so as to hold them positively in place in the tray and are retractable separately to free the ends of the card holders normally lying immediately therebeneath. A further object of the invention is to embody improved means in a tray of standard construction so that the conventional relationship between the card holders and the tray is maintained. Still another object of the invention is to provide individual retaining devices for one or more card holders which shall be simple in construction and operable manually with the greatest convenience when it is desired to remove the card holders retained thereby. A further object of the invention is to provide common means for maintaining the retaining devices in normal position while permitting individual actuation thereof.

In accordance with the invention one end of each of the card holders is engaged by a side flange on the tray, as is usual, while the other end is retained by a plate which is carried at the proximate side of the tray and while normally overlying the said end of the card holder may be retracted to free it.

The invention will be described in greater detail in connection with the embodiment illustrated in the accompanying drawings, wherein:

Figure 1 is a view in plan of a tray embodying the improvements, parts being broken away in the interest of clearness.

Figure 2 is a view in longitudinal section through the tray shown in Figure 1 and taken on the plane indicated by the line 2—2 and looking in the direction of the arrows.

Figure 3 is a view in transverse section through the tray shown in Figure 1 and taken on the plane indicated by the lines 3—3 and looking in the direction of the arrows.

Figure 4 is a fragmentary view on an enlarged scale of the underside of the tray

showing the relation thereto of the improved retaining devices.

Figure 5 is a sectional view taken on the planes indicated by the broken lines 5—5 of Figure 4 and looking in the direction of the arrows.

Figure 6 is a view similar to Figure 4 but looking at the topside of the tray.

Figures 7 and 8 are detailed views in section taken on the planes indicated by the lines 7—7 and 8—8, respectively, of Figure 6.

Figure 9 is a view in perspective of one of the improved retaining plates.

The invention is not limited to the type of tray or card holder employed since it may be embodied in any type of tray and used with any type of card holder which is to be positively retained within the tray.

The tray *a* is illustrated as having a side flange *a'* fixed thereon under which rest the ends of the card holders *b* which fill the tray. At the other side the tray is formed with or carries rigidly a longitudinally extending side flange *a*². Overlying this side flange is a bar *c* which is adapted to reciprocate longitudinally with respect to the flange *a*².

The bar *c* may be formed with a downwardly flange *c'* in proximity to the edge of the flange *a*². The flange *a*² is formed with longitudinally extending slots *a*³ preferably adjacent its opposite ends. In these slots rest sleeves *d* which are secured fixedly to the bar *c* by screws *e* which extend through the bar and have retaining nuts *e'* thereon. By this means the bar *c* may reciprocate longitudinally to the extent permitted by the slots *a*³.

Springs *f* are operatively interposed between the tray and the sleeves *d* so as to maintain pressure on the sleeves and the bar *c* to maintain the bar normally in one extreme position with the sleeves *d* at the ends of the slots *a*³, respectively. The bar *c* can be moved against the action of these springs as will be understood, such movement being limited by engagement of the sleeves *d* with the other ends of the slots, respectively.

Interposed between the reciprocable bar *c* and the fixed flange *a*² of the tray are a plurality of plates *g* which may be of the form illustrated in Figure 9. These plates extend

beyond the inner edge of the flange a^2 so as to overlie the free ends of the card holders b . In this position the inner edges g' of the plates are aligned so as to constitute in effect an uninterrupted retaining flange similar in function to the fixed flange a' along the other side of the tray except that it is sectional and not unitary. The total length of each plate g will depend on the number of 10 card holders which it is intended to overlie. For instance, there might be one plate for each card holder but this is unnecessary in practice it having been found that three to five holders may be safely released at one 15 time without danger of resulting displacement of the other card holders in the tray. As shown in the drawings each plate g is of sufficient length to overlie all or part of four different card holders.

20 Each plate g has at its rear edge an upstanding finger piece g^2 which extends through a slot c^2 provided therefor in the bar c . By engaging this finger piece with the thumb the plate may be conveniently 25 retracted to free the ends of the card holders normally retained thereby.

To guide the plate in its reciprocation it may be formed with two downwardly extending flanges g^3 adjacent its rear edge 30 which may rest in guide slots a^5 provided therefor in the outer edge of the flange a^2 of the tray. A depending flange g^4 may be struck from the plate g' and formed to engage the outer side wall of the tray a in proximity to the inner edge of the flange a^2 to limit positively the inward travel of the plate g , as will be understood from Figure 35 8. This flange on each plate is received by a slot a^4 provided therefor within the flange 40 a^2 .

The bar c is used as a convenient common means for holding all of the plates g in their intended positions while permitting manual reciprocation thereof for the purpose of engaging or releasing the card holders, respectively. Each slot c^2 in the bar c has one convex edge c^3 which is engaged by the finger piece g^2 extending through the particular opening c^2 . In the illustrated embodiment, 45 considering that the action of the springs f is to urge the bar c downwardly as viewed in Figure 1, the convex edges c^3 of the slots c^2 will be formed at the top of said slots. With 50 all of the retaining plates g in normal position overlying the card holders the convex edges c^3 will thus act as detents holding them against accidental displacement under the influence of the springs f . If any one of the plates g is retracted manually it will be 55 constrained to move in a straight path by reason of the engagement of the lugs g^3 with the slots a^5 . Accordingly, the finger piece g^2 riding along the convex edge c^3 will have the effect of moving the bar c upwardly, as 60 viewed in Figure 1, still against the action of

the springs f until the plate is fully retracted and having passed the peak of the convex edge c^3 the bar c will be urged to its normal position by the springs f thereby retaining the particular plate g in retracted position. This momentary reciprocation of the bar c when any one of the plates g is thus retracted will not release the remaining bars but for more than a fraction of time so that the danger of their being accidentally displaced is nil. When the bar completes its rapid reciprocation it will serve not only as a detent for all of the protruding plates but also for any one or more plates which may have been retracted. 70

75 The operation of the device will appear clear from the description given. The tray is essentially one having longitudinally retaining flanges along its opposite sides for the card holders. The improvements permit the retraction of a portion of one of these flanges, as it were, to free the ends of that number of card holders which that fraction of the flange overlies. The other card holders remain undisturbed. The freed card holders may be removed. The broadest aspect of the invention lies in this provision of a sectional retaining flange. The particular means for obtaining this result may be widely changed by a skilled mechanic as may the associated elements for securing the sections in normal position while permitting their movement to free the card holders. For instance, it is possible that the retaining plates g might be hinged on the tray instead of being mounted to reciprocate. The particular construction involving the bar c the plates g and similar details may be changed without departing from the spirit of the invention 90 and equivalent units substituted therefor. 95

100 What I claim is:

1. In a visible index card tray in combination with card holders mounted therein, a plurality of retaining elements each for a predetermined number of holders, and movable separately to release simultaneously all of the holders retained thereby. 110

2. In a visible index card tray in combination with card holders therein, retaining devices for the holders comprising a plurality of elements each normally overlying the ends of a predetermined number of holders, and movable to free simultaneously all of such holders. 115

3. In combination with a visible index card tray and holders therein, a plurality of slidable plates mounted at one side of the tray and normally overlying the proximate ends of the holders, means to mount said plates on the tray for individual reciprocation to free the ends of the holders which they overlie, and yielding means to retain said plates in their extreme positions of reciprocation. 120

4. In a visible index card tray in combination with card holders mounted therein, a plurality of retaining elements each for a predetermined number of holders, and movable separately to release simultaneously all of the holders retained thereby. 130

tion with card holders mounted therein, a plurality of plates mounted at one side of the tray and normally overlying the proximate ends of the holders, finger pieces carried with the plates for individual reciprocation thereof, a reciprocable bar mounted on the tray and having openings through which said finger pieces extend, means carried with the bar and coacting with the finger pieces to hold the plates in their extreme positions of reciprocation, and spring means operatively engaged with the bar to hold it yieldingly against reciprocation upon retraction of any one of the plates.

15 5. In combination with a visible index card tray and card holders therein, a fixed retaining flange at one side of the tray overlying the ends of the holders, a plurality of plates mounted at the other side of the tray and normally overlying the proximate ends of the card holders with the inner edges of said plates in alignment, finger pieces on said plates, a reciprocable bar extending longitudinally of the tray and formed with openings 20 through which said finger pieces extend, said openings having convex edges engaged with the finger pieces, respectively, springs engaged with the bar to maintain such engagement yieldingly, said plates being individually reciprocable transversely of the bar, and means to guide the plates fixedly in such transverse travel.
